(57) **CLAIM**

The ornamental design for an antenna housing, as shown and described.

DESCRIPTION

FIG. 1 is a perspective view of the antenna housing showing the design;

FIG. 2 is a side view thereof;

FIG. 3 is a top view thereof; and,

FIG. 4 is a bottom view thereof.

The broken line showing of the environment in FIGS. 3 and 4 is for illustrative purpose only and forms no part of the claimed design.
